UNITED STATES PATENT OFFICE.

THOMAS F. BOWER, OF FARMDALE, OHIO, ASSIGNOR OF ONE-HALF TO C. A. HOBART, OF KINSMAN, OHIO.

BUILDING-BLOCK.

1,264,606.

Specification of Letters Patent. Patented Apr. 30, 1918.

Application filed March 29, 1915. Serial No. 17,772.

To all whom it may concern:

Be it known that I, THOMAS F. BOWER, a citizen of the United States, residing at Farmdale, in the county of Trumbull and State of Ohio, have invented certain new and useful Improvements in Building-Blocks; and I do hereby declare the following to be a full, clear, and exact description of the invention, such as will enable others skilled in the art to which it appertains to make and use the same.

This invention relates to building blocks, and one of the principal objects of the invention is to provide an interlocking ventilated building block for building a wall having close fitting joints, and said joints being united by a liquid cement to provide an air tight solid substantial wall.

The foregoing and other objects may be attained by means of the construction illustrated in the accompanying drawing, in which—

Figure 1 is a perspective view of a number of building blocks made in accordance with this invention, and interlocked as in the building of a wall,

Fig. 2 is a sectional view taken on the line 2—2 of Fig. 1,

Fig. 3 is a top plan view of one of the blocks,

Fig. 4 is a top plan view of the next adjacent or interlocking block, and

Fig. 5 is a top plan view of a curved block designed for use in building silos.

Referring to the drawing, the numeral 1 designates one of the blocks, and 2 is the interlocking block, the two forms of blocks being utilized for building walls, silos, and other buildings or structures. The block 1 comprises the side bars 3, the end bars 4 and the cross bars 5 and 6 providing four ventilated openings *a* in the blocks. The side members 3 are at their ends provided with shoulders 7 and projecting flanges 8 having plain ends 9. One of the side bars 3, preferably the face side of the block is provided with an angular recess 10 to receive a flange formed on the adjacent block, and at the bottom of the block 1 a flange 11 is provided which fits in a recess in the next adjacent block.

The block 2 is similar in form to the block 1 excepting that it is not provided with the

shoulder 7 at the corners. The block 2 is provided with side bars 3^a and end bars 5^a and 6^a and cross bars 5^a and 6^a. The block 2 is provided with a recess 10^a at its front upper edge to receive the flange 11 on the next adjacent block, while the lower edge of the block 2 is provided with a flange 11^a to fit 60 the recess 10 on the next block.

In building a wall from the blocks described, skilled labor is not required, the blocks are merely placed in position and are interlocked by the flanges 8 and 8^a while the ends 9^a of the block 2 fit against the shoulders of the block 1. The slight space between the ends of the blocks is filled in with liquid cement, thus making a practically air tight wall and a structure which is strong, 70 durable and efficient and of good appearance.

As shown in Fig. 5, the numeral 12 designates the outer curved wall of the block, and 13 is the inner curved wall thereof, said walls being connected by partitions 14 and 15. This block is substantially identical with the others excepting that the sides of the block are curved for forming a curved structure like a silo.

Various changes may be made in the details of construction without departing from the spirit and scope of the invention as defined in the claim.

What is claimed is:—

A wall structure comprising hollow blocks 85 provided at their ends with longitudinally extending overlapping flanges, the flanges of one block of a course having inwardly offset inclined outer sides, and the flanges of an adjacent block of that course having inclined inner sides and straight outer sides aligned with the outer sides of the blocks of that course, the inclined faces of the flanges engaging each other, and each block of each course having the upper edge of its outer 90 side rabbeted and provided at the lower edge of said side with a downwardly extending flange, the flanges of the blocks of one course 95 engaging in the rabbets of the blocks of the next lower course.

In testimony whereof I affix my signature in presence of two witnesses.

THOMAS F. BOWER.
